(57) **CLAIM**

The ornamental design for a monkey-shaped sound device, as shown and described.

DESCRIPTION

FIG. 1 is a perspective view of a monkey-shaped sound device showing my design, as viewed from the top and front.

FIG. 2 is a front elevational view thereof.

FIG. 3 is a back elevational view thereof.

FIG. 4 is a first side elevational view thereof.

FIG. 5 is a second side elevational view thereof.

FIG. 6 is a top plan view thereof; and,

FIG. 7 is a bottom plan view thereof.

The details shown in broken lines illustrate features that form no part of the claimed design.
